UNITED STATES PATENT OFFICE.

ROY A. CRAMER AND JESSE F. CRAMER, OF KANSAS CITY, MISSOURI.

SAFE.

Application filed January 20, 1927. Serial No. 162,351.

Our invention relates to safes and one object is to provide a safe with anchorage means whereby it can be secured from being carried off by unauthorized persons.

5 A further object is to provide a safe with a guarded money slot through which money can be inserted in the safe but not removed therefrom.

Another object is to provide a safe with a 10 combination lock having a removable knob and dial, so that the door can not be unlocked until said knob and dial are replaced.

Other objects will hereinafter appear and in order that the invention may be fully understood, reference will now be had to the 15 accompanying drawings, in which:

Fig. 1 is a front elevation of the safe in anchored position.

Fig. 2 is an enlarged broken front elevation of the safe tipped forwardly at its upper portion to more clearly show the door with its associate mechanism.

Fig. 3 is an enlarged broken sectional view on line 3—3 of Fig. 1.

25 Fig. 4 is a side elevation partly in section of the removable knob and dial.

Fig. 5 is a fragmentary front elevation of the upper portion of the safe with the door opening uncovered.

30 Fig. 6 is a cross section of the anchorage means on line 6—6 of Fig. 3.

Fig. 7 is a fragmentary view looking in the direction of the arrow α , Fig. 3, at the money slot and the guard therefor.

35 Fig. 8 is an enlarged detail view of a plug for closing the money slot.

Fig. 9 is an irregular section on line 9—9 of Fig. 8.

40 Fig. 10 is a fragmentary elevation of the upper portion of the safe showing a modified form of means for securing the plug within the money slot.

Fig. 11 is a cross section of the parts disclosed by Fig. 10.

45 In carrying out the invention we employ a safe indicated generally by the reference character 2. Said safe consists of a pedestal 4 and a money compartment 6, which latter is fixedly mounted upon the former and is preferably of spherical form as shown. The pedestal 4 is preferably of tubular form and reinforced by a rod 7 having its intermediate portion extending through an eye 8 in lugs 10 formed integral with the bottom of 50 the compartment 6. The rod 7 extends downwardly through the pedestal 4 and has its

terminals 12 bent outwardly and upwardly so that when the pedestal 4 is set in concrete as shown by Fig. 1, the terminals 12 will aid in anchoring said pedestal in the concrete. The money compartment 6 has a circular door opening 14 provided with segmental lugs 16 and a pair of keepers 18, which latter are spaced a slight distance apart as shown more clearly by Fig. 5, for 60 a purpose which will hereinafter appear. A circular door 20 is provided for closing the opening 14. Said door 20 is provided near its inner end with peripheral lugs 22 preferably equal in number to the 70 lugs 16, which latter are spaced apart for the passage of the lugs 22 when the door is opened or closed.

The door 20 is arranged to be turned axially so that the lugs 22 may be carried 75 against the rear surfaces of the lugs 16 for the purpose of securing said door in closed position. With this end in view the door is provided at its outer portion with a hub 24 journaled in a complementary opening in 80 the enlarged upper portion of a hinge member 26 which is operably connected by a pintle 28 to a hinge member 30 fixed to the front portion of the money compartment 6. The hub 24 is held in the hinge member 85 26 by the door 20 and a plate 32, which latter overlaps said hinge member and is secured to the hub 24 by suitable means such as screws 34.

In order to facilitate the turning movement of the door 20 the latter is provided with a pair of knobs 36 and the turning movement is limited by a lug 38 projecting forwardly from said door 20 into a segmental recess 40 formed in the adjacent side of the 90 hinge member 26, Fig. 2. The inner portion of the door 20 is provided with a combination lock 42 equipped with a bolt 44 adapted to enter the space between the keepers 18 and prevent the door from being turned to carry 95 the lugs 22 from behind the lugs 16.

The lock 42 is provided with a shaft 46 projecting outwardly through a complementary opening in the plate 32 and terminating in a rectangular end 48 for the reception 100 of a knob 50 whereby said shaft 46 may be rotated for the purpose of either projecting the bolt 44 between the keepers 18 or withdrawing said bolt from between said keepers. The knob 50 has a recessed portion 110 52 conforming to the shape of the terminal 48 over which it is adapted to fit, and said

knob 50 is provided with a dial 54 for co-acting with an index mark 56 on the plate 32 when it is desired to find the combination for unlocking the door 20.

58 designates a detent, Fig. 3, arranged within a recess in the door 20 and pressed outwardly by a spring 60 into a recess 62 in the hinge member 26 after the door has been turned to carry the lugs 22 from behind the lugs 16. Thus after the door has been opened it will be held from turning accidentally and carrying the lugs 22 out of position for passing between the lugs 16 when the door is again pushed into the opening 14. When 15 the door 20 is opened and swung downwardly, it contacts a rubber or other suitable stop 64 set in a recess in the forward portion of the compartment 6 for preventing the front of the door from striking said compartment and thereby becoming marred.

66 designates an elongated money slot arranged in the upper portion of the compartment 6, so that currency can be put in the latter without opening the door 20. The slot 66 is formed by the outer wall of the compartment 6 and three inner walls 21 and 23. In order to prevent the money from being extracted from the compartment 6 by means of a wire or other device inserted through 30 the money slot 66, the lower portion of the latter is curved downwardly or arranged at an angle to its upper portion, Fig. 3, and said lower portion is protected by a surrounding guard 68, the lower margins of 35 which are serrated as indicated at 70, Fig. 7, so that if a person should succeed in impaling a bill or a check upon the lower end of a wire said bill or check will be caught by the guard 68 and thereby be prevented from 40 being withdrawn through said slot 66.

72 designates a plug for closing the money slot 66 into which latter it is adapted to be inserted. Said plug 72 is provided with a lug 74 for engaging a shoulder 76 in the 45 wall of the slot 66 for the purpose of limiting the inward movement of the plug 72, which latter is also provided with a handle 78 whereby it may be readily withdrawn from said slot 66. Means for securing the plug 50 72 within the slot 66 is provided in the form of a catch 78 secured at one end to a spring 80 arranged within a recess 82 in the plug to which it is secured by suitable means such as a screw 84.

55 The catch 78 projects through an opening 86 in the plug 72 and is adapted to enter an opening 88 extending through the lower wall of the money slot 66. The latch 78 reliably holds the plug 72 within the money 60 slot 66 until released by a pin 90 mounted in a case 92 threaded or otherwise secured in the enlarged portion of the opening 88. Normally the pin 90 is held in inactive position by a spring 94 bearing against one end 65 of the casing 92 and a collar 96 fixed upon

said pin 90. After opening the door 20 the plug 72 may be removed from the slot 66 by pulling outwardly upon the handle 78 and at the same time pushing upwardly upon the pin 90, so that the latter will force the 70 catch 78 out of the opening 80.

In the modified form disclosed by Figs. 10 and 11, means have been provided whereby the catch 78^a can be released so that the plug 72^a can be removed from the money 75 slot 66^a without first opening the door 20. Said means consists of a suitable key-controlled lock 98 arranged above the money slot 66^a and provided at its inner end with a rocker arm 100 pivotally connected to a 80 pin 102 arranged in the opening 88^a. By inserting the proper key within the lock 98 the rocker arm 100 can be actuated to cause the pin 102 to push the catch 78^a out of the opening 88^a, so that the plug 72^a can be re- 85 moved.

While the safe may be used in various places it is well adapted for use in gasoline filling stations where it can be anchored in the concrete floor so that it cannot be carried off by burglars. Also by keeping the door 20 normally locked and the knob 50 in possession of a collector who only periodically visits the station for collecting the money, it is apparent that the regular attendants cannot 90 be forced to open the safe by burglars, as would be the case if the knob 50 and the dial 54 were permanent fixtures. As money is taken in through the day, it is inserted into the compartment 6 through the money slot 100 66 for safe keeping until such time as the collector calls with the knob 50. When the filling station is to be closed for the night the attendant closes the money slot 66 with the plug 72, so that a burglar cannot pass a 105 wire through said money slot 66 and attempt to extract money from the compartment 6.

While we have shown two forms of the invention we reserve all rights to such other forms and modifications as properly fall 110 within the spirit and scope of the invention as claimed.

Having thus described our invention, what we claim and desire to secure by Letters Patent, is:

1. In a safe of the character described, a compartment having a door opening and a money slot, a removable plug for closing said money slot, means for securing said plug in the money slot, manually controlled means arranged wholly within the compartment for releasing said securing means so that the plug can be removed, and a door for closing the door opening. 120

2. In a safe of the character described, a compartment having a door opening and a money slot, a door for closing said door opening, a plug for closing the money slot, a spring actuated catch for securing said plug in the money slot, a pin for adjusting said 125 130

catch to inactive position so that the plug can be removed, and a case within the compartment secured to a wall of the money slot and in which said pin is mounted.

- 5 3. In a safe having one compartment with an opening therein, a door for closing said opening, means for locking said door in closed position, walls within said compartment coacting with the wall of the latter 10 in forming an elongated money slot, a removable plug adapted to extend into and close said slot, spring-controlled means car-

ried by said plug for securing the latter within said money slot, a pin accessible only from the interior of the compartment and extending through a hole in a wall of the money slot for adjusting said spring-controlled means to inactive position so the plug can be removed, and spring means for normally holding said pin in inactive position. 15 20

In testimony whereof we affix our signatures.

ROY A. CRAMER.
JESSE F. CRAMER.
